US0D1070842S

(12) **United States Design Patent** (10) **Patent No.:** **US D1,070,842 S**
(45) **Date of Patent:** **** Apr. 15, 2025**

(54) **CALCULATING EQUIPMENT**

(71) Applicant: **CANAAN CREATIVE CO., LTD.**,
Beijing (CN)

(72) Inventors: **Shaohua Zhang**, Beijing (CN);
Nangeng Zhang, Beijing (CN)

(73) Assignee: **CANAAN CREATIVE CO., LTD.**,
Beijing (CN)

(**) Term: **15 Years**

(21) Appl. No.: **29/892,890**

(22) Filed: **May 23, 2023**

Related U.S. Application Data

(62) Division of application No. 29/797,622, filed on Jul. 1, 2021, now Pat. No. Des. 1,019,629.

CLAIM

The ornamental design for a calculating equipment as shown and described.

DESCRIPTION

FIG. 1 is a perspective view of a calculating equipment showing our new design;

FIG. 2 is a front view of the calculating equipment of FIG. 1;

FIG. 3 is a rear view of the calculating equipment of FIG. 1; FIG. 4 is a left view of the calculating equipment of FIG. 1; FIG. 5 is a right view of the calculating equipment of FIG. 1;

FIG. 6 is a top view of the calculating equipment of FIG. 1; and,

FIG. 7 is a bottom view of the calculating equipment of FIG. 1.

The broken lines depict portions of the calculating equipment that form no part of the claimed design.

1 Claim, 7 Drawing Sheets
